VENDING MACHINE

James R. Clem, Dallas, Tex.

Application February 28, 1944, Serial No. 524,192

2 Claims. (Cl. 312—46)

1

This invention relates to new and useful improvements in vending machines.

One object of the invention is to provide an improved vending machine which is particularly adapted to dispense a quantity of bottled goods, such as carbonated beverages of various flavors.

A particular object of the invention is to provide an improved vending machine having a plurality of chambers or compartments for receiving a stack of bottles, together with a conveyor for receiving the bottles from the compartments and conducting the same to an outlet opening through which said bottles are discharged from the machine; each compartment being disposed at an inclination to the vertical so as to permit storage of a greater quantity of bottles in a minimum space and thereby utilizing the weight of said bottles to feed the same to the conveyor by gravity without placing an excessive weight upon the bottles carried by said conveyor.

An important object of the invention is to provide an improved vending machine which may be coin-controlled and having an improved manually-operated ejector mechanism for dispensing one bottle from the unit upon each operation thereof; together with an improved coin receiving mechanism adapted to coact with the ejector mechanism to prevent actuation of the latter until a coin has been inserted in the coin mechanism.

Another object of the invention is to provide an improved vending machine, of the character described, having an improved ejector which is actuated by the manual movement of a lever in one direction to dispense a single bottle, together with a coacting locking mechanism for normally preventing actuation of the ejector by the lever; the mechanism of the ejector being so constructed that the initial movement of the lever, upon insertion of a coin, acts through the coin to release the locking mechanism and permit actuation of said ejector by continued movement of said lever.

A further object of the invention is to provide an improved vending machine, of the character described, wherein the vertically-inclined bottle compartments are formed by a plurality of pivoted plates or partitions whereby access to said compartments for refilling the same is readily had by manually swinging the partitions upon their pivots; each compartment having a pivoted closure at its lower portion for coacting with the bottles supported therebeneath by the conveyor to prevent the discharge of the bottle in said compartment, whereby the compartments are emptied in a predetermined order and the bottles from one compartment cannot be discharged therefrom.

2

until all of the bottles from the preceding compartment have been discharged and no bottle is supported beneath the pivoted closure of said compartment by the conveyor.

5 Still another object of the invention is to provide an improved vending machine, of the character described, having means actuated by the discharge of one of the last bottles from the last-emptied compartment for actuating a coin return mechanism of the usual construction.

A construction designed to carry out the invention will be hereinafter described together with other features of the invention.

The invention will be more readily understood 15 from a reading of the following specification and by reference to the accompanying drawing, wherein an example of the invention is shown, and wherein:

Figure 1 is an isometric view of a vending machine, constructed in accordance with the invention, and having a portion of its casing broken away to show the interior construction thereof;

Figure 2 is an enlarged, isometric view showing the construction of the operating mechanism,

25 Figure 3 is an enlarged, transverse, vertical, sectional view showing the relationship of the operating and locking mechanisms and illustrating the actuation of said locking mechanism by means of an inserted coin,

30 Figure 4 is a transverse, vertical, sectional view, taken at a right angle to Figure 3, and further illustrating the relationship of the operating and locking mechanisms,

35 Figure 5 is a view, similar to Figure 3, showing the operating mechanism upon complete actuation thereof,

Figure 6 is a longitudinal, vertical, sectional view of a portion of the vending machine, and

40 Figure 7 is an enlarged elevation showing the lower portion of one of the compartments of one of the bottle receiving units.

In the drawings, the numeral 10 designates a 45 casing or cabinet which is shown as substantially rectangular and which has its interior divided into an upper or cooling chamber 12 and a lower chamber 13. The cabinet may have its walls constructed of a suitable insulating material in the usual manner and its chambers are separated from each other by a horizontal partition 14 which forms the floor of the upper chamber. The lower chamber 13 has the usual refrigerating equipment (not shown) mounted therein, while a plurality of bottle receiving units A are adapted to be mounted within the cooling chamber 12, only one 50 of which is shown. The number of units will 55

vary in accordance with the number of different kinds of bottle goods to be dispensed, each unit being arranged to receive the bottles of one particular drink or flavor. Thus, if it is desired to dispense two different types of drink, only two units are provided with one unit being disposed along each side of the cabinet as illustrated in Figure 1. By this arrangement, a pre-cooling compartment 15 is provided in the chamber 12 between the units A for receiving and storing the bottled goods prior to their introduction into the units A and this compartment may receive a portion of the refrigerating equipment, such as cooling coils and fan (not shown).

Access to the interior of the upper chamber 12 may be had through a hinged door 16 formed in the top of the cabinet. The door 16 is provided for the purpose of introducing the bottled goods into the chamber 12 and the bottles are ejected from said chamber through a pair of openings 17 formed in the front wall of said cabinet. A downwardly-inclined chute 18 projects through each opening 17 and terminates in a suitable receiving trough 18a, the chute and opening being normally closed by a hinged flap 19, of rubber or other flexible material, as shown in Figure 6. The closing of the chute 18 by the flap 19 prevents the escape of cold air from the interior of the cabinet and said flap is adapted to be swung outwardly by the weight of a bottle falling downwardly through said chute.

Each bottle receiving unit A is of identical construction and, although only two units have been indicated, it is to be understood that any desired number may be employed by merely increasing the size of the cabinet 10. As is clearly shown in Figures 1 and 6, each unit includes a pair of side plates 20 and 21 which are disposed in spaced, parallel relation to each other. A plurality of tie bolts or rods 22 fasten the plates 20 and 21 to each other and are disposed adjacent the lower end of the unit. For fastening the units to each other, an elongate tie rod or bolt 23 extends transversely across the upper portion of the chamber 12 through the plates of each unit and at the forward and rear ends of said chamber. The quantity and disposition of the tie rods 22 is, of course, subject to variation and depends entirely upon the size of unit A. An elongate, flat plate or partition 24 is pivotally connected at its lower end to each rod 22 by means of central hinge members 241 and extends upwardly to the top of the unit. Each partition 24 is of greater length than the distance between its rod 22 and the top of the unit so as to project thereabove when disposed in a vertical plane. For supporting each partition at an inclination, the upper end thereof is bent upon itself and receives an elongate pin 25 which is of a length greater than the width of said partition, whereby the ends of the pin project transversely beyond the partition and engage the upper ends of the plates 20 and 21. Thus, the partitions 24 divide the space between the side plates into a plurality of vertically-inclined chambers or compartments 26, each of which is adapted to receive a stack or row of bottles. It is noted that the forwardmost partition engages and is supported by one of the elongate tie bolts 23 and does not include a transverse pin 25.

For supporting each row of bottles to prevent a premature discharge thereof, a pivoted flap or closure member 27 is carried by each tie rod 22 with the exception of the rearmost compartment. Each closure member 27 has a flange 271

at each side thereof which flanges extend at substantially a right angle thereto and which are pivotally connected to the tie rod. As is clearly shown in Figure 7, the flanges 271 are bent upon themselves around the tie rod to form hinge members having openings 272 which are vertically elongate or oval in transverse section, whereby said flanges are loosely connected to the tie rod and permit transverse movement of the closure member relative to said rod. Due to the provision of the hinge members 241 and 271, the closure members and partitions are movable independently of each other. Each closure member may be of less width than the space between the side plates 20 and 21 and, when swung upwardly to a horizontal supporting position, is below the row of bottles within its respective compartment so as to support said bottles and prevent the discharge thereof (Fig. 1). In this position, the closure members are adapted to overlap each other with their flanges 271 vertically disposed and the tie rods 22 in the upper ends of the hinge openings 272. Each closure member is adapted to be swung downwardly by the weight of the bottles thereabove so as to permit the discharge of said bottles and may be moved manually upwardly to facilitate filling of the compartments as will be hereinafter more fully explained.

For receiving the bottles as they are discharged from the various compartments 26, a conveyor C is mounted within the lower portion of the unit A immediately below said compartments. The conveyor includes a pair of spaced sprockets 28 which are secured upon a rotatable shaft 29, one shaft with its sprockets being suitably supported at each end of the unit and, preferably, having its ends journaled in the side plates 20 and 21 of said unit. A pair of continuous or endless chains 30 pass over the sprockets 28 and carry a plurality of cylindrical rollers 31, of rubber or other suitable material, which are rotatably connected to and extend transversely between the spaced chains. The bottles which are discharged from the compartments 26 fall downwardly onto the conveyor C and are carried therealong by the rollers 31 thereof to the forward portion of the unit and cooling chamber. The conveyor has its discharge end disposed immediately behind one of the chutes 18 in the forward portion of the cabinet as shown in Figure 6, whereby the bottles may be discharged from the conveyor outwardly through said chute.

The distance between the upper run or flight of the conveyor and the pivoted flaps or closure members 27 is such that when a bottle is supported by the rollers 31 upon said upper flight, said bottle will engage the underside of the flap or closure member thereabove. Thus, the closure member is held in a position supporting its row of bottles, as is clearly shown in Figure 1, whereby the bottles upon the conveyor are utilized to maintain the closure members 27 in a position preventing the discharge of bottles from the compartments 26. For maintaining the upper flight of the conveyor in a horizontal plane so that the rollers 31 of said conveyor will be evenly spaced from the closure members, a platform 32 is suitably secured to the plates 20 and 21 beneath said upper flight and said rollers engage and roll upon the upper surface of the platform. With the foregoing arrangement, the row of bottles within the rearmost compartment 26 (not shown) of the unit A is first discharged onto the conveyor C and the bottles upon said conveyor

maintain the closure members 27 of the remaining compartments in a position supporting the bottles therein. As has been hereinbefore set forth, this rearmost chamber has its lower end constantly open due to the omission of the closure member.

After the rearmost row of bottles has been discharged from its compartment and said bottles have been moved forwardly by the conveyor C past the adjacent compartment, the flap or closure member 27 of said adjacent compartment is permitted to swing downwardly to permit the discharge of the bottles therefrom. While this compartment is being relieved of its contents, the remaining or forwardly-disposed compartments are prevented from discharging their bottles because so long as bottles remain upon the conveyor, the closure members of these compartments are maintained in bottle-supporting position. It is only when all of the rearwardly-positioned bottles have been moved forwardly by the conveyor past the next flap or closure member that the same is permitted to swing to an open position and thereby allow the discharge of bottles from the next compartment. In this manner, the bottles upon the conveyor are utilized to coax with the closure members 27 to maintain the same in a position supporting the remaining row of bottles within the compartments 26. It is manifest that the bottles are discharged in a predetermined order from the compartments, the rearmost row being the first to be ejected and the remaining rows being discharged in consecutive succession or sequence.

As the conveyor C is moved forwardly toward the discharge chute 18, the bottles carried thereby are also moved forwardly. The forwardmost bottle will finally drop or fall from the end of the conveyor as the chains 30 of said conveyor move around the forward sprockets 28. As this bottle leaves the conveyor, the neck of said bottle engages a suitable pin (not shown) so as to swing its base forwardly toward the trough 18 and the subsequent forward movement of the bottle may be guided by suitable deflecting means (not shown). Although not illustrated, the chute 18 may be cushioned with flexible or resilient material, while the passage of the bottle through said chute is retarded by the flexible flap 19. Manifestly, the usual trough 18a receives and supports each bottle as it is discharged through the chute. The conveyor C is actuated in a step by step manner, that is, said conveyor is moved a predetermined distance upon each operation. When the conveyor is stationary, a bottle is positioned adjacent the inner end of the chute 18, as is shown in dotted lines in Figures 1 and 6. Upon actuation of the conveyor, this bottle falls therefrom and is discharged through the chute. Each operation of the conveyor moves the next bottle into position immediately adjacent or behind the inner end of the chute.

It is, of course, preferable that the operation of the conveyor be manually controlled and that the manual control, in turn, be locked against operation until the proper coin is inserted. For driving, the forward sprockets 28 in order to transmit movement to the conveyor, the shaft 29 upon which said sprockets are mounted has a reduced sprocket 33 secured to the inner end thereof. And, endless chain 34 connects the sprocket 33 with a drive sprocket 35 which is carried by one end of a stub-shaft 36; the chain 34 extending through openings 37 formed in the

forward wall of the cabinet 10 as is best shown in Figure 2. The sprocket 35 and its stub-shaft 36 are disposed within a small housing or casing 38 which is secured to the forward wall of the cabinet 10 at the central portion thereof. As is clearly shown in Figure 4, a suitable bracket 43 is provided within the housing 38 for supporting the stub-shaft 36. For imparting rotation to the shaft 36 and its sprocket 35, an actuating member or lever 39 has one end thereof journaled upon said shaft so as to be freely swingable relative thereto. The lever 39 includes an arm 40 which projects radially from the shaft and which has a spring-pressed plunger or pin 41 mounted therein. A clutch wheel or element 42 is keyed or otherwise secured to the shaft 36 and is formed with a plurality of radially-extending shoulders 43; the outer periphery of the clutch element being arranged so as to gradually curve from the base of the face of one shoulder to the high point of the adjacent or next shoulder and thereby provide a plurality of lobes 44 as is best shown in Figure 5. The spring-pressed pin 41 is adapted to constantly engage the periphery of the clutch element 42 whereby, when said pin strikes one of the shoulders 44, counter-clockwise rotation will be imparted to said element as well as the shaft 36 upon movement of the lever 39 in a similar direction. However, movement of the lever in a clockwise direction will merely result in a depression of the pin 41 and movement of the same over the lobes 44. Thus, an overriding clutch arrangement is provided whereby rotation in only one direction may be imparted to the stub-shaft and its drive sprocket 35. Although not essential, it is preferable that the clutch element 42 be housed within the lower portion of the lever arm 40 which surrounds a portion of the shaft and is journaled thereupon.

For swinging the lever 39 so as to impart the desired rotation to the shaft, an operating rod 45 extends laterally at a right angle from the upper end of the arm 40 through an arcuate slot 46 formed in one side wall of the housing 38. Thus, by grasping the rod 45 and swinging the same forwardly in a counter-clockwise arc, the arm 40 will be swung in a similar direction to bring about a coaction between the pin 41 and clutch element 42 so as to rotate the sprocket 35 and thereby impart a forward movement to the conveyor C through the chain 34 and sprocket 33. Thus, movement of the conveyor to discharge a bottle is controlled by manipulation of the lever 39 and each time the lever is actuated, a bottle is ejected through the chute 18 in the front wall of the cabinet. A coiled spring 47 connects the arm 40 to the cabinet forward wall for maintaining the lever in an upward, non-operating position with said arm in engagement with a suitable stop member or lug 48, whereby the spring will return said lever to its non-operating position upon release of the rod 45. Upon the lever being swung back to its non-operating position, the sliding of the pin 41 over one of the lobes 44 of the clutch element 42 functions to disconnect said lever from the shaft 36. Therefore, no motion is imparted to the conveyor C upon reverse movement of the actuating lever.

In order to control the operation of the actuating lever 39, a locking mechanism is associated with the shaft 36 and includes a cam wheel 49 which is keyed or otherwise secured to said shaft as shown in Figure 4. A plurality of radially-extending shoulders 50 are formed on the periph-

ery of the cam wheel 49, which periphery is curved gradually from the base of one shoulder to the high point of the adjacent or next shoulder so as to provide a plurality of lobes 51. As is clearly shown in Figures 3, 4 and 5, a spring-pressed plunger 52 is mounted above the cam wheel in a suitable rectangular block or casing 53 which is carried by an upright transverse plate or partition of the housing 38 and which also contains the usual coin rejection mechanism (not shown). When the cam wheel 49 is rotated by counter-clockwise rotation of the shaft 36, one of the shoulders 50 of said cam wheel will strike the plunger 52 so as to prevent rotation of the cam wheel and shaft as shown in Figures 4 and 5. Thus, the shaft cannot be rotated in a counter-clockwise direction until the plunger 52 is retracted so as to be moved upwardly out of the path of the contiguous shoulder 50, whereby its lower end will ride upon the adjacent clockwise lobe 51 as shown in dotted lines in Figure 3. This upward movement of the plunger permits counter-clockwise rotation of the shaft by swinging of the actuating lever 39, which rotation also rotates the cam wheel so as to move one of the lobes from beneath said plunger. Since the lobe curves inwardly to the base of the adjacent, clockwise shoulder, the movement of said lobe from beneath the plunger permits ejection of said plunger into the path of said shoulder (Fig. 5) for preventing subsequent counter-clockwise rotation of the shaft 36 upon the lever 39 being returned to its original position. Due to the provision of the clutch element 42 and the spring-pressed pin 41, the cam wheel remains stationary upon the return of the lever to its non-operating position.

The plunger 52 is adapted to be retracted by a coin which is inserted into an inclined coin chute 54 disposed in the housing 38 and having its lower portion extending through the casing or block 53. As shown in Figures 3 and 5, the lower end of the coin chute terminates adjacent the plunger in a horizontal slot 55 formed in the bottom of the casing 53 and extending forwardly to the front of said casing. The plunger extends downwardly past the slot 55 and has a lug 56 projecting laterally therefrom into said slot in close proximity to the lower end of the coin chute 54. Upon a coin being inserted in the coin chute, it falls downwardly into the slot behind the lug 56 as shown by the dotted line 57 in Figure 3. The lower surface of the lug is bevelled upwardly and rearwardly as shown at 58 for cooperating with the coin. In order to move the coin forwardly into engagement with the bevelled lower surface of the lug, a circular disk or wheel 59 is journaled upon the shaft 36 and is of such diameter as to have a portion thereof disposed within the slot 55, the casing 53 being recessed rearwardly of said slot as shown at 61 to accommodate the disk. As is clearly shown in Figure 4, an annular, spacer collar 60, which is also journaled or freely rotatable upon the shaft, serves to connect the disk to the lever arm 40 and is riveted or otherwise fastened to both said disk and arm. Thus, the disk 59 is rotated simultaneously with the swinging movement of the actuating lever 39 and independently of the shaft upon swinging of said lever in a clockwise direction. An arcuate recess 62 is formed in the periphery of the disk for receiving and supporting the inserted coin in the slot 55 behind the plunger lug 56 when the actuating lever is in its non-operating position. It is noted that the

spring-pressed pin 41 of the lever arm 40 is spaced a slight distance, in a clockwise direction, from the contiguous shoulder 43 of the clutch element 42 when the lever is in its non-operating position as shown by the dotted line in Figure 5. This spacing permits a slight movement of the lever and the disk 59 prior to engagement of the pin 41 with the cam element shoulder 43.

Upon a forward swinging movement of the lever 39 with a coin supported within the recess 62 of the disc 59 so as to be disposed in the slot 55 behind the plunger lug 56, said coin will be moved forwardly in said slot and into engagement with the bevelled lower surface 58 of said lug. Continued forward movement of the coin by the disk will engage said coin beneath the lug so as to lift or retract the plunger, thereby lifting the lower end of said plunger out of the path of the contiguous shoulder 50 of the cam wheel 49. Upon the retraction or lifting of the plunger, forward swinging of the lever will engage the pin 41 with the contiguous shoulder 43 of the clutch element 42 so as to impart counter-clockwise rotation to said clutch element, the shaft 36, its drive sprocket 35 and the cam wheel. Thus, one of the lobes 49 of the cam wheel is moved beneath the plunger for maintaining the same in its retracted position and permitting continued counter-clockwise rotation of the shaft and its connected parts by outward and downward swinging of the actuating lever (Fig. 5). As has been hereinbefore explained, the rotation of the sprocket 35 results in a similar rotation of the sprocket 33 which drives the forward conveyor sprockets 28 for imparting a forward movement to the upper flight of the conveyor C, whereby a bottle is ejected through the chute 18 formed in the forward wall of the cabinet. Since the spacer collar 60 rigidly connects the disk 59 to the arm 40, the continued outward swinging of the lever rotates said disk in a counter-clockwise direction and moves the coin past the plunger lug 56 and out of the slot 55. Upon leaving the slot, the coin is directed toward and falls into a coin box or receptacle 63 which is locked within the lower portion of the housing 38.

Due to the provision of the clutch element 42 and the positioning of one of the cam lobes 51 beneath the plunger 52 prior to the release of the coin, it is manifest that release of the rod 45 before completion of the outward swinging movement of the actuating lever will not result in the premature locking of said lever. Thus, actuation of the conveyor C and the delivery of a bottle is assured upon each insertion of a coin. Each unit A includes a coin return mechanism for returning an inserted coin when all but the last few bottles have been discharged from the forwardmost bottle compartment 26. As is clearly shown in Figures 1 and 6, a lever or arm 64 projects radially from a transverse shaft 65 through a vertical slot 66 formed in the forwardmost partition 24 so as to extend into the forwardmost compartment 26. The shaft 65 is suitably journaled in the side plates 20 and 21 of the unit A and has a rod 67 secured to one end thereof at substantially a right angle so as to project diametrically beyond opposite sides of said shaft. A suitable cable or wire 68 connects one end of the rod 67 to a suitable coin rejection mechanism (not shown) disposed within the housing 38, while the opposite end of said rod is fastened by a coiled spring 69 to one of the tie rods 22. Due to the provision of the spring 69, the shaft 65 is constantly urged in a counter-clockwise direction so as to project the lever 64

through the slot 66 in the forwardmost compartment 26 as shown in Figure 6. With the coin return mechanism in this position, the rejection mechanism within the housing 38 is arranged to reject coins inserted in the chute 54 and direct the same to a suitable opening 70 formed in the forward wall of the housing 38. However, when bottles are disposed within the forwardmost compartment 26 as shown in Figure 1, the lever 64 will be depressed and swung forwardly so as to rotate the shaft 65 in a clockwise direction. This rotation of the shaft pivots the rod 67 in a similar direction so as to pull or move the cable 68 rearwardly, thereby rendering the rejection mechanism within the casing 53 inoperative. Thus, a coin will be received to permit actuation of the lever 39 whenever there are only a few bottles remaining in the forwardmost compartment 26 (Fig. 6) and said coin will be returned to the operator by means of the opening 70 upon the discharge of all except one bottle from said compartment (Fig. 6).

In filling each unit A, access to the interior of the cabinet 10 is obtained through the door 16 which is provided in the top of said cabinet. The upper flight of the conveyor C is filled with bottles by inserting one bottle beneath each closure member and between two adjacent rollers 31. Due to the provision of the hinge openings 272, the closure members 27 may be lifted to permit passing of the bottles over the rollers and thereby eliminate the necessity of operating the conveyor in order to properly position said bottles. Of course, this insertion of the bottles is accomplished by swinging the partitions 24, with the exception of the two forwardmost partitions, upwardly and rearwardly and then placing a bottle beneath the forwardmost closure member. This swinging of the partitions is permitted due to their free upper ends and the pivotal connection of their lower ends with the tie rods 22. The forwardmost compartment 26 may then be filled with bottles and these bottles are supported by the closure member 27 which is held in its horizontal closing position by the bottle previously placed upon the conveyor therebelow. The adjacent partition is then swung forwardly, a bottle is inserted beneath the second closure member and the second compartment may be filled. Manifestly, the remainder of the conveyor and the remaining compartments may be filled in a similar manner upon the forward swinging of the partitions which form their respective walls. It is noted that the bottles used in filling the compartments may be obtained from the pre-cooling compartment 15, with the result that fresh, un-cooled bottles may be placed in this precooling chamber instead of directly into the compartments 26.

As the first bottle is removed from the conveyor, the travel of said conveyor is sufficient to bring the next bottle to position ready for discharge upon the next subsequent operation. This travel of the conveyor also moves the rearmost bottle on said conveyor from beneath the rearmost row of bottles within the last compartment, thereby permitting the next bottle to fall from said compartment onto the conveyor. Therefore, another bottle is automatically fed onto the conveyor C upon the discharge or ejection of each bottle and the upper flight of said conveyor is kept filled at all times. After the last bottle from the rearmost compartment falls into the conveyor, it is carried forwardly by the subsequent travel of said conveyor. As soon as this last bottle moves from beneath the flap or closure member of the

adjacent compartment, said closure member is permitted to swing downwardly and rearwardly and the row of bottles within said compartment is free to fall by gravity onto the conveyor. This next row of bottles is then fed in succession onto the conveyor until the entire row is depleted. When the last bottle is discharged from this compartment and moves from beneath the closure member of the next compartment, said member is permitted to swing downwardly and rearwardly to permit discharge of the row of bottles within the next compartment. Thus, the bottles are discharged from the various compartments in an orderly sequence, beginning with the rearmost compartment and continuing forwardly until the bottles within the forward compartment are finally discharged from the unit. Due to the coaction of the bottles on the conveyor with the various closure members 27, it is impossible for one compartment to be relieved of its contents until the bottles have been discharged from the preceding compartment. The entire feeding of the bottles onto the conveyor is by gravity and since the compartments are relatively shallow, that is, only a relatively few bottles are disposed in each compartment, an excessive weight is not placed on the lowermost bottle which is supported by the conveyor. The inclination of the compartments also materially reduces the total weight imposed upon the lowermost bottle of each compartment. The elimination of this excessive weight provides for an efficient gravity feed without the danger of binding or breaking the bottles.

As has been hereinbefore set forth, each unit A is adapted to receive and store a particular bottled beverage and by providing a plurality of units, a number of bottled beverages may be dispensed from the same cabinet. An actuating lever 39, coin chute 54 and coin return opening 70 are associated with each unit and thus, any of the levers may be selectively actuated to obtain the desired beverage. Since the units A are of identical construction, the manufacture and assembly of the same is facilitated. The space or compartment 15 between the units not only permits the mounting therein of a portion of the usual cooling mechanism so as to cool the interior of the upper chamber 12, but also provides a pre-cooling space or area for the reception of bottles prior to their insertion within the various compartments of said units. By employing the inclined, pivoted partitions 24, the supply of bottles within each unit may be readily as well as rapidly replenished without any danger of breaking said bottles. The inclination of the partitions permits the storage of a maximum quantity of bottles in a minimum amount of space and reduces the weight placed upon the lowermost bottle of each compartment whereby frictional resistance is held to a minimum and an efficient gravity feed is provided.

It is also pointed out that the bottles, in being carried forwardly by the conveyor, are actually rolled between the lower surfaces of the closure members and the rollers of said conveyor. Thus, the bottles revolve in a clockwise direction upon their forward movement and there is substantially no frictional resistance to such movement.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. In a vending machine, a plurality of compartments for receiving articles and having discharge ends, a flap at the discharge end of each compartment for closing the same and retaining articles therein, a transverse pin and slot connection for pivotally mounting each flap, a conveyor in spaced relation to the discharge ends of the compartments, the articles on the conveyor co-acting with the pivoted flaps to prevent the discharge of articles from said compartments, whereby each pivoted flap is held in a position supporting the row of articles in its compartment until the adjacent portion of the conveyor is void of articles, after which the articles may feed from said compartment onto said conveyor by gravity, each slot extending at substantially a right angle to the direction of travel of the conveyor to permit manual movement of said flaps away from said conveyor and flaps upon filling of the machine, and means for discharging articles singly from said machine.

2. The combination set forth in claim 1 wherein each flap is angular and has an upstanding portion bent downwardly upon itself to provide an elongated opening, the pin engaging within the opening to pivotally support the flap.

JAMES R. CLEM.
